JOHN N. REYNOLDS, OF GREENWICH, CONNECTICUT, ASSIGNOR TO WESTERN ELECTRIC COMPANY, OF NEW YORK, N. Y., A CORPORATION OF ILLINOIS.

SERVICE-METER.

1,097,363.

Specification of Letters Patent. Patented May 19, 1914.

Application filed July 27, 1910. Serial No. 574,095.

To all whom it may concern:

Be it known that I, JOHN N. REYNOLDS, a citizen of the United States, residing at Greenwich, in the county of Fairfield and State of Connecticut, have invented a certain new and useful Improvement in Service-Meters, of which the following is a full, clear, concise, and exact description.

This invention relates to service meters 10 for use in telephone exchange systems and is particularly adapted for operation in connection with subscribers' station apparatus to enable the calls to be counted. Its object is to provide a service meter which shall be 15 not easily liable to fraudulent manipulation and which shall be simple, cheap to manufacture, efficient and compact.

In service meters of the class to which this invention particularly relates, the mode of 20 operation is in general such that the subscriber, in initiating a call, actuates a manual key or push button by means of which a switch included in a call circuit is closed, and the operator's attention being thus directed 25 to the call, the service meter is thereafter under her direct control, an electromagnet being provided in association with the service meter whereby either the call may be counted and the mechanism includ- 30 ing the switch restored to normal condition, or the mechanism including the switch be restored without counting the call.

In accordance with the invention, the fraud preventing means comprises a member 35 adapted for advance movement in successive stages and a switch actuated during its movement. This member is advanced in its initial stage by a manually operable key or push button and is subsequently advanced 40 by means wholly independent of the key, the switch being actuated in the latter movement and restored by electrical means also wholly independent of said manual key. Preferably the switch is directly engaged by 45 said movable member and maintained actuated thereby, said member having a third stage of movement during which the switch is restored. This member is preferably in the form of a cam which, in the first stage 50 of its movement, is advanced by direct engagement with the key. A spring pressed lever may engage the surface of the cam in such a way as to oppose its advance movement during the first stage, but to cause the 55 subsequent independent movement thereof.

The subsequent advance movement of the cam after it has caused the actuation of the switch may be arrested by a stop or a series of stops arranged in steps and adapted to be removed in succession by the armature 60 of an electromagnet. This electromagnet may be and preferably is of the type in which a current of one polarity moves the armature in one direction and a current of the opposite polarity moves it in another 65 direction, in either case the stop or stops being moved into and out of the path of a projecting pin on the cam so that the cam is permitted to continue its travel and allow the switch to be restored. The spring 70 pressed lever referred to may be equipped with a pawl for engagement with the ratchet wheel of a registering device, preferably in the form of a counting train. The operation 75 of the registering device is preferably such that the pawl is lifted from the ratchet wheel upon the initial movement of the cam and engages said wheel only upon the retractive movement of the armature after it has been moved in one of its two alternative 80 directions, an interfering device or lever operating to hold the pawl away from the ratchet under all conditions except that occurring when the armature is moved in the proper direction to register a call.

Another feature of the invention lies in the structural arrangement of the stop controlled by the armature of the electromagnet for holding the cam in the position in which the switch is actuated, this stop being arranged in the form of steps whereby upon energization of the electromagnet in either direction, the cam is permitted to move a short distance only and is not fully released until when the current in the line is interrupted the armature returns to its normal position. When the cam is thus moved only a short distance to one of the supplementary stops or steps, the switch remains in its actuated 95 or closed position, the object of this arrangement being to avoid premature interruption of the energizing current.

A further feature of the invention lies in the compact arrangement of the apparatus and its accessibility for inspection and repairs. The operating parts of the mechanism are mounted upon a frame piece secured at the free end of the magnet structure, preferably to the projecting pole pieces 105 of the electromagnet. The cam is pivoted in 110

the frame, near the base or support of the mechanism and the register or counting train is pivoted in the frame away from the base where the numbers on the wheels may be easily seen and read through a window in the covering or casing for the mechanism, and the spring-pressed actuating lever for the register is pivoted between the cam and the register so that it engages the cam at one free end and the ratchet wheel of the register at the other end.

These and other features of the invention, will be readily understood by reference to the accompanying drawings and the 15 appended claims.

In the drawings—Figure 1 is a side elevation of a service meter embodying my invention with the plunger and a portion of its mounting plate broken away to show 20 the arrangement of the actuating pawl and counting train, the mechanism being in normal position; Fig. 2 is a side elevation reverse to that of Fig. 1 with the train of counting wheels removed; Fig. 3 is a view 25 similar to Fig. 2 with the mechanism in an operated condition, the plunger being depressed; Fig. 4 is a front elevation; Fig. 5 is a plan view with the indicator or target broken away; Fig. 6 is a similar view showing 30 the target with its operating mechanism; and Figs. 7, 8 and 9 are fragmentary views showing the various positions the cam may assume, these views being taken from the same side as Fig. 2.

Like reference characters are used to designate like parts throughout the drawings.

The electromagnet 1 is shown as a polarized magnet and consists of two magnet spools 2, 3 connected at the rear by a yoke 10 of magnetic material 4, the said magnet spools being mounted in a vertical plane upon a base 5 of brass or other non-magnetic material by front and rear supports 6, 7. The rear support being secured to the 45 yoke, is also preferably of brass. The usual permanent magnet 71 is secured to the middle of the yoke-piece and extends forward through an opening in the support 6 and terminates close to the armature. The forward ends of the magnet cores project 50 through and are firmly fixed in the upright support 6. The said support has forwardly extending arms 8, 9 for supporting an armature 30 centrally pivoted thereupon by pivots 36, 37.

The elements above set forth are well known and their combination as shown is merely a matter of design, and may be modified to suit different conditions. I will, 60 however, now describe a structure having the above well known elements and in addition the mechanism by which I am enabled to carry out my invention.

In accordance with the invention the support 6 is in the form of a flat frame plate,

and its integral armature supporting arm 9 is extended and carries at its outer end a lever 10 pivoted below its center. This lever carries a pivoted pawl 11 at its upper extremity adapted to engage and advance a ratchet wheel 12 and thereby the train of counting wheels 12'. The lower extremity of the lever 10 carries a roller 13 pivoted thereto by a pivot pin 14. The lever 10 has an arm 15 extending laterally from the pivotal point of said lever to the extremity of which is secured one end of a spiral spring 16, the other end of which is anchored to a guideway 17 for the plunger 18, said guideway extending laterally from an integral 80 forwardly extending arm 19 of the front support 6.

The mounting plate 6 has a forward extension 20' from which projects an upright supporting arm 20 for a triangular cam 21, pivoted at its center to the upper extremity of said arm. This cam enables power to be stored up in the coiled spring 16 through the agency of the lever 10, simultaneously removing the control of its disposition to 90 the operator, who will release it in one of two ways according to whether the call has been successful or unsuccessful. To enable rotation of said cam by said plunger a series of pins 22, 23, 24 project from the outer face of the cam, one for each cam face, situated equidistant from each other and upon the depression of the plunger, one of said pins is engaged thereby and the cam rotated. Upon the inner face of said cam 21 are also located three similar pins 25, 26, 27. The relation of these sets of pins to each other is such that upon the depression of the plunger and rotation of the cam, one of the inner stops or pins 25, 26, 27 rotates 105 into engagement with a stop 28 controlled by the armature (see Figs. 3 and 8), just as the roller 13 rides over onto a high point of the inclined plane formed by the succeeding cam face, the cam being then locked. The outward movement of the lower end of lever 10 by the cam surface upon which the roller 13 may be riding causes the arm 15 to move downwardly and stretch the coiled spring 16, and since the cam is locked in this position, power is stored up in said coiled spring to be released upon the movement of the armature and removal of stop 28 controlled thereby. The independent advance of the cam by the roller after it has 110 reached a succeeding cam face, upon the depression of the plunger, enables the plunger to be given a depressive movement just sufficient to rotate the cam until the succeeding cam face is reached, when further depression is prevented, it being remembered that soon after the succeeding bearing surface is reached one of the inner pins 25, 26 or 27 engages the stop 28 controlled by the armature and further movement of 115 120 125 130

the cam is arrested. The cam is then maintained under tension due to the engagement of the spring-pressed roller with a high point of the plane.

5 A pair of switch springs 31 is anchored to the base 5 in a suitable insulating mounting 32 with their free ends directly under the cam 21 and adapted to be brought together upon the rotation of said cam 21, to notify 10 the operator that the subscriber wishes a connection. It is preferable to so arrange these springs with respect to the said cam that they will remain open until the roller 13 has reached the succeeding cam face, 15 when it will be remembered the cam is locked, and since the subscriber must depress his plunger a sufficient distance to lock the cam, the closure of the switch springs is insured and further manipulation 20 thereof prevented, the release of the cam and consequent opening of the switch being thereafter under sole control of the operator through the agency of the electromagnet which, by the movement of its armature, 25 removes stop 28.

Having thus described the means for storing up energy and placing the disposal of the same entirely under control of the operator, the manner in which the electromagnetic alternative release means operates and by virtue of which she is enabled to either dissipate this stored up energy or use the same to advance the counting train and record a call will now be described.

30 As was previously stated, the armature is pivotally mounted so as to be displaced either way according to the character of current impressed upon the line by the operator. While the cam stop 28 may be attached directly to the armature I prefer to leave the armature entirely free to have a limited movement either way before being called upon to do any work, since it has been found that in a structure wherein the armature is called upon to begin work from a state of rest, it has a tendency to respond improperly, while if given a little play it invariably responds properly. Therefore, 45 in the present case the cam stop 28 is a pin carried upon a rectangular-shaped support 28' soldered to a U-shaped plate 33. The plate 33, supported by and movable about the pivots 36 and 37, lies before and within the plane of the armature and serves to 50 transmit motion from the armature to one of a pair of L-shaped plates 34, 35. These plates maintain the plate 33 centrally supported free of the armature. They are pivoted upon the common armature pivots and 55 have openings 57, 58 on opposite sides of their pivotal points in which are fastened coiled springs 38, 39, respectively, anchored to suitable rearwardly-extending arms 40, 41. These springs maintain adjustable stops 42, 60 43, carried by the respective plates, against

the ends of plate 33, and maintain end stops 44, 45 of the respective plates 35, 34, the former adjustable, against the cores 59, 60, the stops 42, 43 serving to maintain the plate 33 yieldingly neutral over the armature. 70 To enable the operator to have a check on the operation of the mechanism, *i. e.*, to determine whether it has responded to the charging current, a pair of holdover stops or pins 46, 47 are also carried by the support 28' and are adapted to engage and hold said cam in a position to maintain the contacts 31 closed as long as the operator holds her key depressed, which is usually long enough to allow a signal to light to indicate 80 that the mechanism has responded. This position of the parts is shown in Fig. 9.

The plate 35 is extended on the side next the lever 10 to form an upwardly extending arm 48, the upper extremity of which is inclined forwardly and normally engages the rear end of the pawl 11 pivoted at its middle point to the upper extremity of the lever 10. A coiled spring 50 is attached at one end to said pawl forward of its pivot 90 point and at its other end is attached to a retaining pawl 51 for the ratchet 12, although these pawls may just as well have separate springs. The arm 48 either prevents the pawl 11 from advancing the ratchet 12 or permits the same to engage and advance the same as will presently be described.

In order to provide a ready means of informing the subscriber whether his call has 100 been charged or not, a target 62 is provided adapted to be controlled by the movement of the armature and to display the words "Charged" or "Rebate" before a window 66. The arrangement is such that the target 105 remains in the position last moved and is only moved by a movement of the armature oppositely to the way it was last operated. This may be accomplished in any well known manner. As shown the armature 110 may have an arm extending through an opening in the target and engaging one side or the other thereof according to the direction in which the spring 64 pulled the target when the armature was last rocked, said 115 spring being secured to the pin 65, upon which the target is pivoted.

It will be evident that when the mechanism is in the position shown in Figs. 3 and 8 and an impulse of current impressed upon 120 the line of the proper character to cause the electromagnet to displace the armature so that the upper portion thereof is attracted to the pole 59 the stop 28 will be removed, permitting the cam to rotate for a limited 125 distance until said pin 28 engages the hold-over contact 47, said contact maintaining the switch 31 closed as long as the operator maintains her key closed and the armature attracted, which will be until she gets the 130

proper signal that the mechanism has responded. The attraction of the upper end of the armature has caused the lower end to move freely for a limited space and then 5 to engage and tilt plates 33 and 35 upon their pivots. As before stated, the plate 33 serves the purpose of transmitting the armature movement to either plate 34, 35 according as the armature is displaced. The 10 displacement of plate 35 causes the arm 48 to move backwardly clear of engagement with the rear of actuating pawl 11, whereupon the spring 50 becomes active to pull the forward portion or tooth of said pawl 15 down into engagement with tooth 61 of ratchet 12. This would be the next position to that shown in Fig. 3, the position of the cam being shown in Fig. 9. Upon the release of the key by the operator, the hold-over contact 47 is removed from engagement with stop 28 which permits the cam to 20 rotate to normal, whereupon the lower end of the lever carrying the roller 13 partakes of an inward movement under the influence of spring 16, and the upper end carrying the pawl has a positive forward movement and, being in engagement with the tooth 61, advances the ratchet wheel 12 and thereby the train of counting wheels one step. 25 The target thereupon displays the word "Charged" before the window 66. If on the other hand, the connection had been unsuccessful, an impulse of current would be impressed on the line by the operator of the 30 proper character to cause the electromagnet to swing its armature so that the lower portion thereof is attracted to the pole face 60. In such event the upper portion of the armature after reaching the limit of its unobstructed movement, will lift plates 33 and 34 and tilt the same on their pivots. The hold-over stop 46 will now engage pin 27 and upon the release of the key by the operator the said holdover stop is removed and the 35 lower end of the lever moves inwardly as before, its roller 13 riding over the inclined cam surface until it reaches its lowest point. Simultaneously with the inward movement of the roller 13 the upper end of the lever 10 and consequently the pawl 11 then has an outward movement as before, but the ratchet is not advanced, since the arm 48 carried by plate 35 is not moved, and consequently said arm remains in contact with the rear 40 of the pawl 11 during its entire forward movement, said pawl sliding over tooth 61, and at the limit of its movement resting in notch 52. The arm 63 moves to the other side of the opening in the target and causes 45 the same to swing to the opposite position and display the word "Rebate."

Referring now to the form of the individual bearing surfaces of the cam it has been found that the particular contour or 50 configuration shown has proven most effi-

cient in service. It will be noted that the cam surfaces are not perfect inclined planes, but are slightly rounded and that the portion beginning with the point where the roller rests when locked is a comparatively great distance from the center or pivoted point and the distance from that point to the lowest point on the plane where the roller normally rests is comparatively very short. Therefore, when the stop is removed, the roller rides down a steep slant portion, so to speak, and since the pawl 11 is at this moment in engagement with tooth 61, ready to perform the work these series of operations were leading up to, it is given a positive forward movement in the passing of the roller from a high point on the plane to the lowest point, which has been found invariably effective to advance the counting train. 85

I claim:

1. In a service meter the combination with a manually operable key, of a member adapted for advance movement in successive stages, said member being moved in the first stage under control of said key, means for imparting a subsequent advance movement to said member independent of said key, a switch actuated by said member in said independent movement, and electromagnetic means controlling the restoration of said switch. 90

2. In a service meter, the combination with a manually operable key, of a cam adapted to be advanced in successive stages, said cam in the first stage being under control of said key, a spring-pressed lever opposing the movement of said cam during the first stage and causing its movement during the second stage, the movement of said cam in its second stage being independent of said key, a switch actuated in said second stage, and electromagnetic means controlling the restoration of said switch. 105

3. A service meter having a movable cam, a manual key for initially actuating the same, a device opposing initial movement thereof and thereafter causing further movement beyond the range of said key, a switch adapted to be closed in said further advance, and electromagnetic means controlling the opening of said switch. 110

4. A telephone service meter having an electromagnet with its armature, a cam adapted to move in three successive stages, a manual key for moving it in its first stage, a spring-pressed lever for moving it in its second stage independent of said key, a switch associated with said magnet closed by said cam in said second stage, a stop controlled by said armature for locking said cam in its second stage under the tension of said spring-pressed arm, with said switch closed, the energization of said magnet causing said armature to remove said stop, 120 125 130

whereupon said arm rotates said cam in its third stage in which said switch is opened.

5. In a service meter, the combination with a device adapted to rotate, a manual key for rotating the same, energy storing means actuated by said device in said rotary movement, means for locking said energy storing means, a register, and electrically controlled means for releasing said energy 10 storing means and permitting the same to actuate said register.

6. In a service meter, the combination with a cam, a manual key for initially rotating the same, energy storing means actuated and locked by said cam, a register, and discriminative means controlled electrically for releasing said cam and thereby said energy storing means and permitting the same either to actuate said register, or preventing 20 the same in its restoration to normal position from actuating the register.

7. A registering mechanism having a rotatable cam, a counting train, an actuating lever therefor, a spring maintaining said 25 lever in engagement with said cam, manual means for rotating said cam and deflecting said lever to store up energy in said spring, a stop for locking said cam with said lever deflected and said spring under tension, and 30 electromagnetic means for releasing said cam, whereupon said spring causes said lever to rotate said cam and simultaneously advance said counting train.

8. A service meter having an electromagnet and its armature, said armature being mounted to rock in bearings, a counting train, an actuating pawl therefor, manually-operable means for moving said pawl to an off-normal position, means for maintaining said pawl in said position under tension, means controlled by said armature for releasing said pawl, and an arm controlled by said armature engaging said pawl to prevent the same from advancing said 40 counting train upon the tilting of the armature in one direction and adapted when the armature is rocked oppositely to move away from said pawl to permit the same to advance said counting train.

50. 9. In a service meter, the combination with an electromagnet, a tilting armature, a counting train, an actuating pawl therefor, a lever carrying said pawl, a pivoted cam, a spring for maintaining said lever in engagement with said cam, a manual key for rotating said cam, thereby deflecting said lever, moving said pawl and storing up energy in said spring, a stop for locking said cam in its actuated position, said stop 55 being withdrawn upon the displacement of the armature, and an arm controlled by said armature and lying normally in the path of movement of said pawl to maintain the same ineffective to advance said counting train upon the displacement of the armature.

ture in one direction, the said arm being withdrawn to permit the pawl to engage and advance said counting train upon the displacement of the armature in the opposite direction.

10. In a service meter the combination with a manually operable key, of energy storing means controlled thereby, a member adapted to be advanced by said means independent of said key, a switch actuated by said member in said movement, a stop for limiting the advance of said member, means for removing said stop to permit a further advance of said member, and a register, said register being actuated by said energy storing means and said switch being restored during said further advance of said member.

11. A service meter, the combination with a device adapted to be advanced in successive stages, a manual key for advancing said device in its initial stage, energy storing means actuated in said stage, said energy storing means causing said device to advance in its second stage, independent of 90 said manual key, a switch actuated in said independent advance, a stop for arresting said device in the second stage of its advance movement, a register, and electrically controlled means for removing said stop and permitting said energy storing means to advance said device in its third stage in which said register is actuated and said switch restored.

12. A service meter having an electromagnet and armature therefor, a switch, means for actuating and locking said switch, means governed by said armature adapted upon its initial movement to partially release the locking means while maintaining said switch actuated, and means actuated upon a subsequent movement of the armature for finally releasing said locking means and restoring said switch.

13. A service meter having an electromagnet and armature therefor, a pivoted cam, a manual key for initially moving said cam, means for imparting a subsequent independent advance movement to said cam, a switch actuated by said cam during said subsequent advance movement, a stop controlled by said armature and adapted to arrest said independent advance movement, said stop being removed upon the attraction of said armature, a supplementary stop adapted to again arrest the cam while maintaining said switch closed, said supplementary stop being removed upon the retraction of the armature, whereupon said cam continues its advance movement and said switch is restored.

14. A service meter comprising an electromagnet, a base therefor, a frame secured at the free end of said magnet, a cam movable in said frame near the base, a register 130

- carried in said frame near its outer end, manual means for moving said cam, and an actuating lever for said register adapted upon the movement of said cam to become operative to actuate said register.
15. A service meter comprising an electromagnet, a base therefor, a frame secured at the free end of said magnet, a cam movable in said frame near the base, a register mounted in said frame at its outer end, manual means carried by said frame for moving said cam, and an actuating lever pivoted to said frame and engaging said cam at one free end and said register at the other adapted upon the movement of said cam to become active to actuate said register.
16. A service meter comprising an electromagnet, a base therefor, a frame plate secured to the projecting poles of said magnet, a cam pivoted to said frame near the base, a register carried by said frame at the outer end, a manual key for moving said cam, and an actuating lever pivoted to said frame and adapted to be rendered active by the movement of said cam to actuate said register.
17. A service meter comprising a base, an electromagnet mounted thereon, a frame plate secured to said base and having open-

ings through which project the pole pieces at the free end of said electromagnet, an armature therefor pivoted to said frame, a cam pivoted to extensions of said frame plate near the base, a counting train mounted upon said frame near its upper end, a spring-pressed lever pivoted to said frame and having one free end bearing on said cam and carrying at its opposite end an actuating pawl for said counting train, and a plunger adapted to reciprocate in said frame plate and rotate said cam to deflect said lever and cause its pawl to advance said counting train.

18. In an electrically controlled meter, the combination with a counter, of an automatically returning, manually advanced actuator therefor, said counter being advanced on the return movement thereof, a movable armature for holding the actuator in advanced position, and an electromagnet under the control of a distant station for operating said armature and releasing said actuator.

In witness whereof, I, hereunto subscribe my name this 26th day of July A. D., 1910.

JOHN N. REYNOLDS.
